Patented Apr. 5, 1960

187,618

VENDING MACHINE FOR CANDY AND THE LIKE

Walter E. Moore, Bel-Nor, Mo., assignor to National Vendors, Inc., St. Louis, Mo., a corporation of Missouri

Application February 2, 1959, Serial No. 54,408

Term of patent 14 years

(Cl. D52—3)

FIG. 1.

FIG. 2.

FIG. 3.

FIG. 4.

Fig. 1 is a top plan view of a vending machine for candy and the like showing my new design;

Fig. 2 is a front elevation of Fig. 1;

Fig. 3 is a right side elevation of Fig. 2; and,

Fig. 4 is a perspective view of the machine.

The rear of the vending machine is plain and unadorned.

I claim:

The ornamental design for a vending machine for candy and the like, substantially as shown and described.
